UNITED STATES PATENT OFFICE

147,102

DESIGN FOR A FISH LURE

Louis D. Adams and Nelia G. Poplin, Ponca City,
Okla., assignors to Pachner & Koller, Inc., Chi-
cago, Ill., a corporation of Illinois

Application February 14, 1946, Serial No. 126,546

Term of patent 7 years

(Cl. D31—4)

To all whom it may concern:

Be it known that we, Louis D. Adams and Nelia G. Poplin, citizens of the United States, residing at Ponca City, in the county of Kay and State of Oklahoma, have invented a new, original, and ornamental Design for a Fish Lure, of which the following is a specification, reference being had to the accompanying drawings, forming part thereof.

Figure 1 is a perspective view of a fish lure showing our new design.

Fig. 2 is a side view thereof.

Fig. 3 is a top plan view thereof.

Fig. 4 is a front view thereof.

Fig. 5 is a rear view thereof.

We claim:

The ornamental design for a fish lure, as shown.

LOUIS D. ADAMS.
NELIA G. POPLIN.
